UNITED STATES PATENT OFFICE.

BENJAMIN F. BROWN, OF FITCHBURG, MASSACHUSETTS, ASSIGNOR TO BROWN BAG FILLING MACHINE COMPANY, OF FITCHBURG, MASSACHUSETTS, A CORPORATION OF MASSACHUSETTS.

ASSEMBLING APPARATUS.

1,235,284.

Specification of Letters Patent. Patented July 31, 1917.

Application filed September 3, 1912. Serial No. 718,270.

To all whom it may concern:

Be it known that I, BENJAMIN F. BROWN, a citizen of the United States, and resident of Fitchburg, county of Worcester, State of Massachusetts, have invented an Improvement in Assembling Apparatus, of which the following description, in connection with the accompanying drawing, is a specification, like characters on the drawing representing like characters on the drawing representing

10 like parts.

In United States Patent No. 752,373 granted to me February 16, 1904, an apparatus is shown and described for facilitating the handling and sealing of envelopes or bags each containing a plurality of smaller sealed bags containing different seeds or other articles, the large bags being brought to the sealing devices on a traveling conveyer.

A later Patent No. 877,900 granted February 4, 1908 to J. R. Brown, designed for use in connection with the first mentioned apparatus, embodies a series of bins for containing the small bags or envelopes having different varieties of seeds or similar articles therein, and a distributing reservoir in front of each bin, to contain a supply of the envelopes, in condition for easy handling.

The conveyer referred to in my prior patent is arranged with its upper run in front of the 30 reservoirs, and as the large envelopes or bags are carried along by the conveyer operatives take the required number or set of small sealed bags from the reservoirs and place them in each of the large bags, the latter thereafter being conveyed to the sealing or fastening mechanism substantially as disclosed in my prior patent.

The practical operation of this assembling apparatus has disclosed certain features 40 which tend to slow down or impede the progress of the operation as a whole, for the large bags or envelopes lie flat upon the conveyer in such a way that time is lost in opening them up for the reception of the 45 small envelopes.

So, too, the bags change their position on the conveyer and the operatives have to handle them more than is desirable.

My present invention has for its object the 50 production of an assembling apparatus which will be free from the above noted objections, and in the present embodiment of my invention I have provided the traveling conveyer with means whereby the large empty bags or envelopes when placed thereon

will be positioned most favorably for filling and for transfer thereafter to the fastening mechanism with a minimum of handling.

The apparatus in which my invention is embodied conserves time and energy on the 60 part of the operatives, and the output of the apparatus as a whole is largely increased.

The various novel features of my invention will be fully described in the subjoined specification and particularly pointed out 65 in the following claims.

Figure 1 is a front elevation, centrally broken out, of an assembling apparatus embodying one practical form of my present invention, it being understood that the end 70 portions of the apparatus are a long distance apart in actual practice;

Fig. 2 is a transverse sectional view on the line 2—2, Fig. 1, looking toward the left;

Fig. 3 is an enlarged view of a portion of the upper run of the conveyer when seen from the front of the apparatus, the nearer anti-friction rolls being removed;

Fig. 4 is a top plan view of the structure 80 shown in Fig. 3;

Fig. 5 is a perspective view, detached, of a side stop for use in connection with the bag or envelop supports on the conveyer.

Hereinafter the word "bag" is used as a 85 comprehensive term to indicate the bag, envelop or other similar receptacle which is to be filled with a plurality or set of small filled packages or envelopes.

Referring to Figs. 1 and 2 I have indicated at A the series of bins which are to contain the filled and sealed packages or envelopes which are to be inserted, one from each bin, into the large bags, the number of such bins used depending upon the number 95 of different kinds of seeds or other articles which constitute a set.

The bins are each provided with a door, as B, through which a portion of the contents of a bin is withdrawn from time to time into a distributing reservoir C, formed by the front wall of the series of bins and a longitudinally extended, inclined board D.

The trough thus formed is separated into reservoirs by partitions, as C^x, and if desired 105 such partition may be a continuation of the bin-dividing partition A^x, the parts so far described being substantially as shown in Patent No. 877,900 referred to, and supported on a suitable frame work E, E', Fig. 2.

Referring to Fig. 2 I have shown a duplex apparatus, that is, with two traveling conveyers, at the front and back, respectively, of the series of bins A, so that the bins are 5 provided with front and back doors, and a series of distributing reservoirs, C, will be provided at the back of the machine as well as at the front thereof.

As will be understood hereinafter, however, my invention comprehends either a 10 single or a duplex arrangement of the apparatus.

The bin portion of the apparatus is located at one end thereof, and at the other 15 end, at a distance from the bins, I locate one or more fastening mechanisms, as F, of any suitable character, with a shelf-like work support w below them and an overhanging, forwardly-projecting flange w³ 20 above said support, all substantially as in my Patent No. 752,873 referred to.

The work-support has a V-shaped opening w' in front of each fastening mechanism, and the back-stop w² is provided, Fig. 1, as 25 in my prior patent.

In practice the entire apparatus may be 30 from thirty to forty feet, or more, from end to end, according to the character of the work to be performed, and the bins and fastening mechanisms will be at a height from the floor convenient for operation by attendants seated before them.

At each end of the apparatus I provide 35 suitable framework, as G, Fig. 1, for the support of rotatable drums H, H' on which is mounted an endless, flexible belt conveyer I, one of the drums being driven from a suitable source of power, (not shown) by a belt J and pulley K attached to the drum H'.

If the duplex form of apparatus be used 40 the conveyer at the front will, in its construction, fittings, and operation be duplicated at the back of the apparatus, hence only one conveyer will be described in detail.

The upper run of the conveyer travels 45 upon a flat horizontal, shelf-like support L carried on suitable brackets of the frame E', and below the reservoirs C and the work-support w, but in front thereof, so that packages can be taken conveniently from the reservoirs and inserted in bags on the conveyer, the filled bags being thereafter lifted onto the work-support w, as in the patents before mentioned. The support L is provided with 50 front and back ledges l, l' between which the upper run of the conveyer travels and is guided.

Heretofore the empty bags have been 55 pinched or "fulled" to open their mouths, and then laid on the upper run of the conveyer, necessitating considerable and undesirable handling in their passage in order to place the small envelops in the bags.

To obviate this I have provided the 60 conveyer with a series of bag supports each of

which, when on the upper run of the conveyer, is adapted to coöperate with and maintain a bag in an upright and preferably slightly inclined position with its open mouth uppermost, whereby as the open-mouthed bags are moved past the distributing reservoirs the sealed envelops or packages taken therefrom can be dropped into the bags without any handling of the latter. 70

As will appear hereinafter the bag supports are so constructed that the empty bags can be applied thereto instantly and full bags can be as quickly removed to be fastened or sealed. 75

The bag support may be made in various 80 forms, and herein I show one convenient structure, comprising a thin sheet metal plate 1 having tubular, laterally separated eyes 2, 3 at its upper and lower edges, the eyes 3 being interposed between similar eyes 4 formed on a foot plate 5, a pintle 6 connecting the two sets of eyes to form a hinge joint. 85

The eyes 2 are interposed between similar eyes 7 formed on the upper edge of a metal 90 plate 8 constituting a strut or brace, and pivotally connected with the support 1 by a rod 9 extended through the eyes 2 and 7, Fig. 4, the ends of said rod extending beyond the bag support for a purpose to be referred to. 95

At the bottom said brace is provided with eyes 10, which are interposed between eyes 11 on an anchor 12 and pivotally connected thereto by a pintle 13, the anchor 5 being seated on the foot plate 12 and secured thereto by suitable rivets 14 which attach the latter to the conveyer. 100

The brace 8 of a bag support is spaced apart therefrom such a distance that the support 1 will be maintained at the desired 105 angle with relation to the upper run of the conveyer, the bottom of the opened bag M resting between the lower end of its support and the pivotal connection between the next brace 8 beyond and the conveyer, as shown at 110 the right, Fig. 1.

As the conveyer travels around the convex surface of the drum H, or H', the pivotal connection between each bag support and its back brace permits the requisite change in the angle between said parts, the jointing or articulation of the bag supports and their braces together and to the conveyer giving all requisite flexibility and preventing cramping or distortion. 115

The opened bags will be placed against the supports 1 as the latter assume their proper operative position, shown at the right, Fig. 1, and the supported and positioned bags will be moved past the distributing reservoirs C, where operatives are stationed to fill the bags, and the filled bags are then conveyed to the vicinity of the fastening mechanisms F. 125

As they reach this locality the filled bags 130

are removed, their open mouths are closed, and the bags are piled up on the work support *w* to await the final fastening operation, as in my prior patent.

5 To safeguard the bags from any accidental displacement transversely of the conveyer I have devised a side guard or stop, which can be applied removably to the bag support at either side thereof, the stop when 10 positioned preventing lateral movement of the bag at that side of the support.

Referring to Fig. 5 the stop or guard, preferably made of resilient sheet metal, comprises a flat body bent up at one end at 15 and slotted to present a central tongue 16 and the shorter side portions 17, the tongue being struck up slightly from the plane of the body, and preferably it is downturned at its tip, at 18.

20 The guard is applied to the edge of the bag support, the parts 17 passing behind and the tongue 16 in front of the support, which latter is centrally slotted at 19 to receive the tip 18 of the tongue, and I also 25 prefer to notch the side edge of the support, at 20, to receive the upset or bent root of the tongue, this arrangement maintaining the side stop or guard at a fixed distance from the conveyer and locked upon the bag 30 support, the resiliency of the guard assisting in so doing.

By making the side stop reversible as to the bag support the conveyer equipped with bag supports can be used interchangeably 35 at the back or front of the apparatus without any alteration other than to shift the stops from one to the other side of the bag supports.

Herein the stops are set to prevent any 40 transverse movement of a bag off its support toward the back of the conveyer.

It will be noted that the stops do not interfere in the least with the placing or removal of the bags.

45 The bag supports and their adjuncts, even when made as light in weight as is compatible with strength and durability, will add quite materially to the dead load of the conveyer, and this is particularly the case 50 when long runs of 40 feet or more are used.

Hence the strain upon the conveyer would be injurious and would cause rapid wear of the conveying mechanism unless the lower run of the conveyer were supported between 55 the drums, and I have shown means for supporting the lower run of the conveyer in such manner that it is not subjected to any material strain.

Referring to Fig. 1 it will be seen that 60 as the bag supports pass around the drum *H* they are brought into a depending position beneath the part of the conveyer constituting the lower run thereof, and upon the transverse rods 9 I mount anti-friction 65 or bearing rolls 21, said rolls being mount-

ed to rotate freely on the projecting ends of said rods.

These rolls are separated from the adjacent eyes 2 in any suitable manner, as by a washer and cotter-pin device 22, and in 70 a similar manner each roll is retained on its rod, at 23.

As the braced bag supports swing downward the bearing rolls 21 are brought into engagement with a flat and slightly inclined 75 track 24, Fig. 1, and the rolls travel upward thereon until they pass therefrom onto a horizontal section of the track 25, this latter section being extended the major portion of the length of the apparatus.

From the section 25 the bearing rolls 21 travel down the inclined section 26 until they pass from its lower end when the corresponding bag supports are carried around the drum *H*.

By the arrangement described the lower run of the conveyer 1 is supported in a horizontal plane for the greater part of its length, so that none of its adjuncts add their weight from one to the other end of the 80 track section 25, and as will be apparent the inclined sections 24, 26 support all but say four or five of the depending bag supports.

It is preferable to use the inclined approaching section 24 and an oppositely inclined leaving section 26 because thereby the support of the lower run of the conveyer is gradually transmitted through the supports 1 and braces 8 to the section 24 and the belt 100 is gradually elevated to horizontal position, while the support of the conveyer is gradually withdrawn by the inclination of the section 26.

By the construction shown there is practically no sag whatever to the lower run of the conveyer and as there is substantially no stretch I am enabled to dispense with tension means or belt tightening devices.

When the bag supports are on the upper run of the conveyer they are subjected to very little strain, but both the supports and their back braces are put under compression on the lower run, and operate in the manner of an articulated truss to sustain the lower run.

Various changes or modifications in details of construction and arrangement may be made by those skilled in the art without departing from the spirit and scope of my 120 invention as set forth in the claims hereunto annexed.

Having fully described my invention, what I claim as new and desire to secure by Letters Patent is:

1. In an apparatus of the class described, a series of distributing reservoirs, a bag fastening mechanism at a distance therefrom, an endless traveling conveyer having its upper run in front of and adjacent said 130

reservoirs and fastening mechanism, a series of bag supports on the conveyer, to sustain the bags in upright position along the upper run of the conveyer, and means acting 5 through said bag supports when on the lower run of said conveyer to sustain the latter.

2. In an apparatus of the class described, a series of distributing reservoirs, bag closing means at a distance therefrom, an endless traveling conveyer having its upper run in front of and adjacent said reservoirs and closing means, and a series of bag supports mounted on the conveyer and adapted when on the upper run thereof to sustain the bags 10 in substantially upright position with their mouths uppermost.

3. In an apparatus of the class described, a series of distributing reservoirs, bag closing means at a distance therefrom, an endless traveling conveyer having its upper run in front of and adjacent said reservoirs and closing means, a series of bag supports mounted on and permanently connected with the conveyer, to sustain bags on the upper 20 run thereof in a substantially upright position with their mouths uppermost, and a brace connecting each support and the conveyer, to maintain the support in an upright and slightly inclined position when 25 on the upper run of the conveyer.

4. In an apparatus of the class described, a series of distributing reservoirs, bag closing means at a distance therefrom, an endless traveling conveyer having its upper run 35 in front of and adjacent said reservoirs and closing means, a series of bag supports pivotally connected at their lower ends with the conveyer, and a back brace pivotally connected with the conveyer and with the 40 upper end of each bag support, to maintain the latter in operative position relative to the conveyer while permitting relative movement at the ends of the runs.

5. In an apparatus of the class described, 45 a series of distributing reservoirs, a bag fastening mechanism at a distance therefrom, an endless traveling conveyer having its upper run in front of and adjacent said reservoirs and fastening mechanism, a series 50 of bag supports on the conveyer, to sustain the bags in upright position along the upper run of the conveyer, a fixed track beneath the lower run of the conveyer, and bearing rolls carried by the bag supports and adapted 55 to travel on said track when the supports are on the lower run, to thereby sustain and prevent sagging of the lower run of the conveyer.

6. In an apparatus of the class described, 60 a series of distributing reservoirs, a bag fastening mechanism at a distance therefrom, an endless traveling conveyer having its

upper run in front of and adjacent said reservoirs and fastening mechanism, a series of alternating bag supports and back 65 braces connected with the conveyer and regularly spaced apart lengthwise thereof, each brace connected with a bag support to position the latter on each run, bearing rolls supported by the connected portions of each 70 support and its brace, and a fixed track below the conveyer and upon which the rolls travel, to sustain the lower run of the conveyer.

7. In an apparatus of the class described, 75 a series of distributing reservoirs, a bag fastening mechanism at a distance therefrom, an endless traveling conveyer having its upper run in front of and adjacent said reservoirs and fastening mechanism, a series 80 of bag supports on the conveyer, to sustain the bags in upright position along the upper run of the conveyer, and means, including a fixed track below the conveyer and having a horizontal central section and inclined end 85 sections, to act through the bag supports when on the lower run of the conveyer and sustain the lower run thereof.

8. In an apparatus of the class described, 90 a plurality of distributing reservoirs, a bag fastening mechanism at a distance therefrom, a work-support in co-operative relation to said mechanism, a traveling conveyer passing in front of and adjacent said reservoirs and fastening mechanism and below 95 the work-support, to convey bags filled from said reservoirs to the vicinity of the work-support, and devices on the conveyer to engage and sustain the bags with their mouths uppermost as they are moved along the front 100 of said reservoirs.

9. In an apparatus of the class described, a series of distributing reservoirs arranged in a row, a bag fastening mechanism at a distance therefrom, an endless traveling conveyer having its upper run passing in front of and adjacent said reservoirs and the fastening mechanism, to present bags to be filled from the reservoirs and to convey filled bags thence to the fastening mechanism, and a series of regularly disposed devices on the conveyer to engage and sustain the bags, while on the upper run, in substantially upright position with their mouths uppermost, whereby the filling of the bags 110 from the reservoir is facilitated. 115

In testimony whereof, I have signed my name to this specification, in the presence of two subscribing witnesses.
